UNITED STATES PATENT OFFICE.

JOHN ROBERT WEATHERSBY, OF MIDDLESEX, NORTH CAROLINA.

CLEVIS.

1,099,000.

Specification of Letters Patent.

Patented June 2, 1914.

Application filed January 3, 1914. Serial No. 810,203.

To all whom it may concern:

Be it known that I, JOHN ROBERT WEATHERSBY, a citizen of the United States, residing at Middlesex, in the county of Nash 5 and State of North Carolina, have invented new and useful Improvements in Clevises, of which the following is a specification.

This invention relates to clevises for plows and similar farming implements.

10 One object of the invention is to produce a clevis of simple and improved construction which may be readily applied to a plow beam which will be held securely in position when applied and which will permit of vertical adjustment of the draft.

A further object of the invention is to produce a clevis of the character described which will permit of convenient detachment and replacement of the draft link.

20 With these and other ends in view which will readily appear as the nature of the invention is better understood, the same consists in the improved construction and novel arrangement and combination of parts 25 which will be hereinafter fully described and particularly pointed out in the claims.

In the accompanying drawing has been illustrated a simple and preferred form of the invention, it being, however, understood 30 that no limitation is necessarily made to the precise structural details therein exhibited, but that changes, alterations and modifications within the scope of the claims may be resorted to when desired.

35 In the drawing, Figure 1 is a side elevation partly in section, showing the front end of a plow beam equipped with the improved clevis. Fig. 2 is a horizontal sectional view taken on the line 2—2 in Fig. 1. Fig. 3 is a perspective view showing the position occupied by the parts when the draft link is to be exchanged or adjusted.

Corresponding parts in the several figures are denoted by like characters of reference.

45 The improved clevis includes in its construction top and bottom members 15, 16 which when combined and juxtaposed form a U-shaped member adapted to be mounted on the forward end of a plow beam B. The 50 top and bottom members may be described as consisting of plates or bars fitted upon the upper and lower faces of the plow beam and provided at their forward ends with arms or brackets 17, 18 which are provided 55 with terminal overlapping lugs 19. The top

and bottom members are provided near their rear ends with apertures 14 for the passage of a fastening pin or bolt 20. Said top and bottom members are also provided near their forward ends with keyhole slots 21 for the passage of a fastening bolt or member 22. It is obvious that the plow beam is to be provided with apertures alining, respectively, with the apertures 14 and the keyhole slots 21 for the passage of the bolts or fastening members 20, 22. Said fastening members may be threaded at their lower ends for the reception of nuts or for engagement with the apertures in the bottom member 16 which may be correspondingly threaded, as seen at 60 23, although within the scope of the invention other well known means may be adopted for retaining said fastening members in position. The fastening members 20 and 22 are, moreover, provided at their upper ends with heads 24 constituting wrenches for 65 general use.

A draft plate 25 is provided, said draft plate being provided at its forward edge with forwardly extending pins 26 to engage apertures 27 in the arms or brackets 17, 18. The rear side of the draft plate is provided with recesses 28 adapted to accommodate a draft link 29, said draft link being confined in one of said recesses by engagement with the front end of the plow beam, as clearly seen in Fig. 1. The draft plate is provided at its upper and lower ends with heads 30 having reduced portions or shanks 31. The 70 keyhole slots 21 are of such dimensions as to permit the draft member to pass through the wide portions thereof, after which by moving said draft member in a forward direction, the shanks 31 will engage the narrow portions of the keyhole slots, thereby retaining the draft plate securely in position and at the same time engaging the pins 26 75 with the apertures 27. When the parts are assembled, as seen in Fig. 1, the draft link 80 will be held securely in one of the recesses 28 by engagement with the front end of the plow beam; the draft link will prevent displacement in a rearward direction of the draft plate; and the draft plate will lock the top and bottom members 15 and 16 together 85 against spreading movement by engagement of the pins 26 with the apertures 27.

As will be seen from the foregoing description, taken in connection with the drawings hereto annexed, I have produced a 90 95 100 105 110

clevis of simple and improved construction which may be readily and quickly applied to a plow beam. By detaching the forward fastening member or bolt 22, the clevis may 5 be swung to one side of the beam, and the draft plate may now be slid back in the key-hole slots 21 and removed, after which the forward ends of the top and bottom members may be moved apart for the removal or 10 replacement of the draft link. The latter may thus be readily adjusted from one to another of the recesses 28. The proper adjustment having been made, the parts are reassembled as before, and the device is 15 ready for use. The construction, as will be seen, is extremely simple, and it has been proven to be thoroughly efficient for the purposes for which it is provided.

Having thus described the invention, what 20 is claimed as new, is:—

1. A device of the class described comprising substantially L-shaped top and bottom members combining to form a U-shaped body and having front arms provided with 25 apertures and with overlapping tongues, said top and bottom members being provided near their rear ends with apertures and near their front ends with keyhole slots, fastening members engaging said apertures and 30 keyhole slots, and a draft plate engaging the keyhole slots and having forwardly extend-

ing pins engaging the apertures in the front arms of the top and bottom members.

2. The combination with a plow beam, of a clevis comprising top and bottom members having front arms provided with apertures and with overlapping lugs, said top and bottom members being also provided with apertures near their rear ends and with keyhole slots near their front ends, fastening members extending through the plow beam and engaging said apertures and key-hole slots, and a draft plate provided with recesses in the rear side thereof and with forwardly extending pins engaging the apertures in the arms of the top and bottom members, said draft plate being also provided at the upper and lower ends thereof with heads engaging the top and bottom members and having reduced portions forming shanks that 50 engage the narrow portion of the keyhole slots; and a draft link engaging one of the recesses in the draft plate and retained therein by engagement with the forward end of the plow beam when the parts are assembled.

In testimony whereof I affix my signature in presence of two witnesses.

JOHN ROBBERT WEATHERSBY.
